UNITED STATES PATENT OFFICE.

FRANK J. FREY, OF QUINCY, ILLINOIS.

DESIGN FOR A STOVE.

No. 38,156.

Specification for Design.

Patented Aug. 7, 1906.

Application filed June 22, 1906. Serial No. 322,975. Term of patent 3½ years.

To all whom it may concern:

Be it known that I, FRANK J. FREY, a citizen of the United States, residing at Quincy, in the county of Adams and State of Illinois, have invented a new, original, and ornamental Design for Stoves, of which the following is a specification, reference being had to the accompanying drawing, forming part thereof.

The figure is a perspective view of a stove, showing my new design.

I claim—

The ornamental design for a stove, as shown.

FRANK J. FREY.
